TION OF THE DISTRICT OF COLUMBIA

RADIOMOVIE LANTERN SLIDE

Application filed January 29, 1931. Serial No. 512,181.

This invention relates to radiomovies and television receivers, and has for its principal object large receiving-screen projection from a lantern slide, the density of the latter of which can be changed by incoming radio signals in elementary areas of the whole lantern slide surface.

Basically the new concept may consist of a liquid lantern slide, horizontally located, in which bubbles are formed to change the lighting of the slide at the bubble location.

These bubbles are formed at the elementary area points of the picture area to build up a figure, projected on a screen. As the bubbles rise and burst at the surface, new bubbles are formed, and in new places, and the figure formed thereby changes; namely, a new type of motion picture.

The bubbles formed in the fluid lantern slide represent the changing figure or scene at the radio broadcast station.

Again if this lantern slide can be located in the projector beam of a powerful light source, obviously any size receiving screen can be brightly illuminated.

These elementary area bubble points preferably lie in 48 rows of 48 bubble points each, namely, 2304 elementary points in the whole lantern slide, a standard adopted by the Radio Manufacturers' Association. The bubble point locations are determined by tiny wires fixed in the lantern slide.

With these and other objects in view the invention consists of the novel combination of elements hereinafter described, illustrated in the drawing, and pointed out in the claim.

In the drawing, Fig. 1 is a schematic illustration of the assembly of elements; Fig. 2 a top view of the lantern slide; Fig. 3 a sectional view of the slide; Fig. 4 a reduced drawing of the lantern slide and its scanning disc in operative relation; and Fig. 5 the contact brush lying at the end of each of the 48 radial wires of the scanning disc.

In the figures A is a lantern slide; B the transparent scanning disc; C the source of light; D condenser lenses for concentrating the light through the lantern slide by reflection from the mirror E; and onto the screen

(not shown) reflected from the second mirror F; and through the lens G.

The lantern slide is made up of a tray A, of lead, for example, with a transparent bottom therein, A', Fig. 3. This transparent bottom is studded with tiny wires, located in rows, with an equal number of wires in each row, and these wires are submerged in an acidulated solution, A''.

The scanning disc, B, has radially located wires, B2, B2, B2, leading from the segments of a commutator, B3, at the hub. There are as many such radial wires as there are rows of wire points in the lantern slide. The outer end of each wire on the scanning disc is tipped with a contact brush, B4, shown in Fig. 5. These brushes are spirally located, that is, each is at a shorter radial distance from the hub than the preceding one; and these radial differences are equal to the separation of the rows of tiny contact wires in the lantern slide.

Assuming the scanning disc to be put into rotation, with the brush, B4, making contact with the successive wires of the several rows of them in the bottom of the lantern slide, the complete electric circuit would then contain (1) a wire from the radio amplifier to the commutator, (2) the commutator, (3) a radial wire of the scanning disc, (4) a terminal wire in the bottom of the lantern slide, (5) the acidulated solution, (6) the lead margin of the lantern slide, and (7) the wire leading back to the other terminal of the amplifier.

Current flowing in this circuit creates a bubble at the submerged wire which is at the moment a part of the circuit. This bubble soon reaches a size where it breaks loose and rises to the top of the solution and bursts. During this whole time the light passing through the bubble so effects the projected light from the source C that it is imaged on the screen, for example, as a lighter spot than the surrounding fluid if the latter is colored.

If, therefore, the scanning disc is put into motion the several terminal brushes on the disc will contact with all the lantern-slide wires in each row of them, and with all the rows in succession.

As the current from the amplifier of the radio set to the scanning disc is intermittent, an intermittency determined by the incoming radio signals, it will be seen that the bubbles will occur intermittently and at different places on the surface of the liquid lantern-slide.

If the scanning disc is in synchronism with the analytical mechanism at the broadcast station, then these succession of bubbles will form an image of the person, object or scene at the broadcast station.

With the scanning disc rotation 900 R. P. M., that is, for a new picture every fifteen-thousandth of a second, the contact time for each wire is about one-thirty-five thousandth of a second.

The depth of the liquid determines the time the bubble persists, and, of course, is controllable. One-tenth of a second persistence has been found to produce quite sharp motion pictures.

The contact time between scanning disc brush and lantern slide wires being constant, the size of the bubble will depend on the voltage applied, a small bubble for low voltages, and a large bubble for higher voltages. Therefore as the halftones at the transmitting station gives but half voltage values, these lower voltages at the receiving station produce halftone values in the received bubble picture.

The process rather closely follows the principle of the halftone printing block used in newspaper illustrations. As the groups of small dots representing the halftone areas and groups of the larger dots the darker portions, so in these lantern-slides, the size of the bubbles in different groups determines the contrasts in the picture.

It has been found that physical contact between the scanning disc brushes and the studs in the lantern slide is not necessary to produce the results sought. If the brush passes within sparking distance of the stud, bubbles will be formed and produce just as satisfactory a picture as if actual physical contact were made instead of spark contact.

What I claim, is—

In apparatus of the class described, a source of light, a liquid lantern slide through which light from said source may pass, a transparent scanning disc in operative relation to said lantern slide, and means carried by said scanning disc whereby bubbles may be formed in said liquid lantern slide.

In testimony whereof I have affixed my signature.

CHARLES FRANCIS JENKINS.
